UNITED STATES PATENT OFFICE.

WALTER MORIEN CAUGHLAN, OF RICHLAND, IOWA, ASSIGNOR TO LOREN HINSHAW
AND GEORGE L. MORAIN, OF RICHLAND, IOWA.

COMBINATION STEP-LADDER AND IRONING-BOARD.

1,119,243.

Specification of Letters Patent.

Patented Dec. 1, 1914.

Application filed April 15, 1914. Serial No. 831,994.

To all whom it may concern:

Be it known that I, WALTER M. CAUGHLAN, a citizen of the United States, residing at Richland, in the county of Keokuk and at 5 State of Iowa, have invented a new and useful Combination Step-Ladder and Ironing-Board; and I do hereby declare the following to be a full, clear, and exact description of the invention, such as will enable others 10 skilled in the art to which it appertains to make and use the same.

This invention relates to a new and useful improved combination step ladder and ironing board, and an object of the invention 15 is the provision of a step ladder, which may be used as such pure and simple without being lumbered or made awkward by holding and supporting or carrying some other attachment, such as the ironing board, 20 but which step ladder may be adjusted or arranged to provide supporting legs to support an ironing board.

In practical fields the details of construction may be subjected to alterations, falling 25 within the scope of what is claimed.

The invention comprises further features and combination of parts, as hereinafter set forth, shown in the drawings and claimed.

In the drawings:—Figure 1 is a view of the 30 step ladder constructed in accordance with the invention. Fig. 2 is a view of the step ladder adjusted or arranged to support an ironing board. Fig. 3 is a rear view of Fig. 1. Fig. 4 is an enlarged detail view, showing 35 the connection between the upper end of one of the rearwardly inclined legs of the ladder and the upper end of the ladder. Fig. 5 is an enlarged detail view of one of the rearwardly disposed legs, showing the 40 connection between the same and the ironing board.

Referring to the drawings, 1 and 2 designate the two parts of the step ladder, the part 1 comprises the usual side bars 3 having the top step or board 4 connected thereto and a plurality of steps 5 arranged between and secured to the side bars 3. One of the steps 5 is provided with a flange 6 constituting a stop, an abutment or brace, as will 45 hereinafter appear. A pair of chains 7 connect the parts 1 and 2, to prevent said parts from spreading too far, when adjusted for use as a step ladder, as shown in Fig. 1. Said chains 7 are adjustably connected to 50 the part 1, so as to adjust the part 2 closer to the part 1. The part 2 comprises the side bars 8 and 9, braced or reinforced relative to one another by means of the braces 10. The lower ends of the braces 10 abut or engage the flange 6 or stop or brace, when 55 the parts 1 and 2 are arranged or adjusted as shown in Fig. 2, to hold and brace the part 2 in position. The side bars 3 of the part 1 at the upper portions adjacent the board or step 4 have secured to their outer 60 faces plates 11 by means of screws 12. These plates are provided with headed lugs 13, which engage the elongated portions 14 of the slots 15 of the plates 16, which are secured at 17 by the screws to the upper ends 65 of the bars 8 and 9 of the part 2. When the parts 1 and 2 are arranged as shown in Fig. 1, the heads of said lugs 13 lie substantially at right angles to the elongated portions 14 of said slots 15, to secure the 70 lugs against disengagement with said slots. When the parts 1 and 2 are arranged as shown in Figs. 1 and 2 to support an ironing board, headed lugs 19 (which are similar to the lugs 13) of the plates 11 also engage the 75 elongated portions 14 of said slots 15, in such a manner as to prevent disengagement with said slots. Also when the parts 1 and 2 are arranged as shown in Fig. 2, the side bars 8 and 9 of the part 2 engage the flanges 80 21 of the plates 22, which are secured to the side bars 3 of the part 1, to assist in holding and bracing the parts 1 and 2 in position. Said flanges 21 overhang the bars 8 and 9 to hold them in place. The lower ends of 85 the bars 8 and 9 are beveled off as shown at 23, to maintain a firm bearing on the surface upon which said parts 1 and 2 rest. The lower end of the bars 3 also have beveled off portions 24, to attain a firm bearing 90 on the surface upon which said parts 1 and 2 engage. One edge of the board or step 4 has a pair of pins, designed to pierce the ironing board, as shown in Fig. 2 to prevent displacement, said pins being designated by 95 the character 25.

The invention having been set forth, what is claimed as new and useful is:—

1. In combination, a pair of parts having detachable connections for holding the same 100 connected for use as a step ladder, said parts adapted to be arranged to intersect one another, one of said parts having a series of steps, one of which is provided with a flange, said part having the steps being pro- 110

vided with plates provided with overhanging flanges, the other part designed to intersect the part having the steps and engaging between said flange and the flanges of 5 said plates to hold the parts in position to support an ironing board.

2. A step ladder comprising two parts having detachable connections at two of the adjacent ends, one part having a plurality 10 of steps constituting a ladder, the other part constituting a brace for the part having the steps, a pair of chains connecting said parts to prevent said parts from spreading too far when used as a step ladder, the part having 15 the step comprising side bars, plates secured to the side bars provided with overhanging flanges, one of said plurality of steps having a flange constituting an abutment, the brace

parts adapted to intersect the part having the said steps and engaging between said overhanging flanges and the abutment and disposed at an angle thereto and arranged to support an ironing board, a part of said detachable connection of the brace part designed to detachably connect to said ironing board, said brace part having braces, the lower ends of which engage said abutment to assist in bracing said parts. 20 25

In testimony whereof I have signed my name to this specification in the presence of 30 two subscribing witnesses.

WALTER MORIEN CAUGHLAN.
